UNITED STATES PATENT OFFICE.

ARTHUR P. SCOTT, OF CHICAGO, ILLINOIS, ASSIGNOR TO CHILE EXPLORATION COMPANY, OF NEW YORK, N. Y., A CORPORATION OF NEW JERSEY.

CASTING-MOLD.

1,226,123.

Specification of Letters Patent. Patented May 15, 1917.

Original application filed November 17, 1915, Serial No. 61,904. Divided and this application filed February 1, 1916. Serial No. 75,477.

To all whom it may concern:

Be it known that I, ARTHUR P. SCOTT, a subject of the King of Great Britain, residing at Chicago, county of Cook, and State 5 of Illinois, have invented certain new and useful Improvements in Casting-Molds; and I do hereby declare the following to be a full, clear, and exact description of the invention, such as will enable others skilled in 10 the art to which it appertains to make and use the same.

This invention relates to casting molds, and particularly to molds for casting magnetite electrodes, which are so constructed as 15 to facilitate the removal of the electrodes from the molds, and also the production of electrodes of uniform properties.

Molten magnetite, suitable for the production of magnetite electrodes, can be produced, for example, by melting the ore in 20 an electric furnace. The molten magnetite, when ready for pouring, is at a temperature of about 1590° C. In order to produce from this molten magnetite electrodes which will 25 be free from defects, it is important that the molds be capable of quick handling in order that the electrodes may not remain therein longer than desired, and in order that the electrodes may be stripped from the 30 molds with facility. In the production of hollow electrodes, and even in the production of solid cast electrodes, it is often important that means be provided for insuring that the top of the electrode shall not harden 35 before the remainder, and for maintaining a body of molten magnetite extending above the top of the mold until a portion of the magnetite has solidified to form a shell within the mold.

40 The novel mold of the present invention is of particular value for such purposes, and enables hollow electrodes to be produced therein, and even solid electrodes, in a particularly advantageous manner.

45 The invention is illustrated in the accom-

panying drawings showing one embodiment thereof, and the invention will be described more particularly in connection therewith.

In the drawings,

Figure 1 shows the mold in perspective, 50 and in a horizontal position, supported by the yoke, parts of which have been broken away;

Figs. 2 and 3 are respectively bottom and 55 top views of the mold;

Figs. 4 and 5 show the parts of the mold separated;

Fig. 6 is a sectional view of the detachable top or extension; and

Fig. 7 shows the mold in an upright position, supported in the yoke, and with the top extension thereon.

The mold, as shown is made up of the two parts 1 and 2, held together by pivoted bolts 3 and keys 4. The mold parts are, with advantage, made of cast gray iron. By careful foundry work the interior surface can be made sufficiently smooth to eliminate all machine work except at the joint planes. This natural surface presents several points of 60 advantage over a machined surface, being more resistant to the molten magnetite, and having less tendency to warp, as well as being less expensive to produce.

For convenience of handling, the mold is 65 mounted on trunnions, to permit of its rotation in a vertical plane. These trunnions 5 are shown as arranged one on each of the mold parts. The mold is carried by a suitable conveyer such as an overhead trolley 80 and chain block having a supporting yoke in which the trunnions are mounted. This yoke is made up of an upper frame member 7 and hook members 6.

A pouring funnel or top 8 forming an extension of the mold, is arranged thereon, so that it can be removed by sliding and with a shearing effect upon the material within the mold. In the production of hollow magnetite electrodes it is advantageous to 85 90

connect the pouring funnel or top 8 to the supporting yoke, so that it will be removed when the mold is inverted, without the necessity of removing it as a separate operation.

5 In using the mold for the production of magnetite electrodes, it is usually pre-heated to about 350° C. so that the chilling effect upon the magnetite will not be too great, and 10 so that the cracking of the electrode will be prevented. In practice, the mold may also be given a coating of lime or other suitable material, to reduce the tendency of the magnetite to stick thereto.

15 Where it is desired to produce hollow electrodes, the magnetite is poured from the mold after a shell of solid magnetite of the desired thickness has been formed therein. The mounting of the mold on trunnions facilitates 20 the quick pouring of this molten magnetite.

In casting electrodes, and particularly hollow magnetite electrodes, in an open mold, it was found difficult to obtain an 25 electrode with a perfect neck. In the time interval allowed for a solid wall of magnetite to form within the mold, a thick skin formed over the top of the magnetite, which had to be broken through before the interior 30 magnetite could be discharged. This left a ragged membrane at the mouth of the electrode which could not be removed without cutting off the entire neck. If the neck is kept open by agitation of the molten interior 35 with a bar, the wall of the magnetite is rapidly chilled at this point, causing unevennesses in the thickness of the wall, and setting up strains which often caused failure of the electrodes during annealing.

40 This difficulty is overcome by the use of the hot top or funnel, which rests upon the top of the mold during pouring, and forms in effect a funnel or extension of the mold. After a wall of solid magnetite has formed within the mold, and while the interior body of magnetite is still molten, the hot top or funnel can be removed with a shearing effect, thereby leaving the solid wall of magnetite of uniform 45 thickness. This funnel can be knocked off without inverting the mold, as where it is desired to retain the molten magnetite within the mold for further periods of time. In the apparatus illustrated, with the funnel 8 connected by a chain to the top of the yoke in which the mold rotates, this funnel is automatically removed with a shearing effect when the mold is inverted.

50 After the electrode has been produced within the mold, the mold can be quickly laid in a horizontal position on a stripping table, the pivotal support of the mold in its yoke facilitating this procedure. The keys can then be quickly knocked out and the

upper half of the mold lifted off, thereby 65 permitting the electrode to be lifted from the lower half of the mold and conveyed to an annealing furnace or chamber.

The arrangement of the mold in its support, and the fastening of the mold parts 70 together, permit ready handling of the mold, including removal of the mold from its supporting yoke, and separating of the mold parts from each other. Where the mold is of considerable thickness, it may 75 with advantage be split diagonally along its major axis so that the electrode can be removed without binding. With thinner electrodes, there is less danger of binding at the corners, and the use of a diagonally split 80 mold may not be necessary.

It will of course be understood that the size and proportions of the mold can be varied, and that its details of construction can also be varied, without departing from 85 the invention, which comprises a mold which can be readily handled and taken apart and which provides for the production of magnetite electrodes in a particularly advanta- 90 geous manner.

The method herein disclosed is claimed in my co-pending application, manufacture of electrodes, Serial No. 61,904, filed November 17, 1915.

I claim:

1. A sectional metal mold for casting magnetite electrodes having pivots on which it may be swung end for end to pour out the liquid magnetite after a shell has formed in contact with the mold and means for shearing one end of said shell at the time of pouring out said liquid. 95 100

2. A metal mold for casting magnetite, said mold having a plurality of parts readily detachable from one another, a trunnion on each of said parts forming a transverse axis on which said mold may be swung to pour out the liquid magnetite after a shell has formed within said mold, and automatic means operative during said swinging for 110 shearing one end of the casting while still hot; substantially as described.

3. A metal mold for casting magnetite, said mold comprising two parts readily detachable to release the casting while still 115 hot, said mold having pivots on which it may swing to pour out the liquid magnetite after a shell has formed in the mold and a removable top section forming an extension of said parts and capable of being removed from 120 the mold with a shearing effect.

4. A mold for casting magnetite, said mold being of cast iron and split diagonally into two parts, readily detachable means for securing said parts together, a trunnion on each part to provide a transverse axis on which said mold may be swung end for end to pour out liquid magnetite after a shell has 125

formed within the mold and a pouring funnel forming an extension of said parts and removable therefrom with a shearing movement.

5. A mold structure comprising a divided mold, means for pivotally supporting the same, a removable top section forming an

extension thereof, and means for removing said top automatically when the mold is inverted in said support; substantially as described. 10

In testimony whereof I affix my signature.

ARTHUR P. SCOTT.
